[57] **CLAIM**

The ornamental design for a combined container cap and set of lighter refill adaptors, as shown and described.

DESCRIPTION

FIG. 1 is a perspective view of a combined container cap and set of lighter refill adaptors showing my new design;

FIG. 2 is a top plan view;

FIG. 3 is a bottom plan view;

FIG. 4 is a side elevational view thereof;

FIG. 5 is an exploded view of FIG. 1 showing the adaptors removed from the cap; and

FIG. 6 is a bottom plan view with the adaptors removed.
